DOOR LATCH MECHANISM

Dorr Miller, Detroit, Mich., assignor to Dura
Company, Toledo, Ohio, a corporation of Ohio

Application April 8, 1935, Serial No. 15,280

3 Claims. (Cl. 292—254)

This invention relates to door latch mechanisms, but more particularly to latches for refrigerator doors and the like, and an object is to produce a new and improved latch mechanism of this character, which is simple in construction, inexpensive to manufacture, has relatively few parts, and contains the features of construction and design hereinafter described.

Other objects and advantages will hereinafter appear, and, for purposes of illustration, but not of limitation, embodiments of the invention are shown on the accompanying drawings, in which:

Figure 1 is a sectional view of a latch mechanism mounted on the door and body of a refrigerator;

Figure 2 is a side elevation of the latch shown in Figure 1;

Figure 3 is an end view elevation of the latch shown in Figure 1;

Figure 4 is a sectional view of an alternate form of latch mechanism;

Figure 5 is a vertical sectional elevation on the line 5—5 of Figure 4; and

Figure 6 is a front view in elevation of a portion of a refrigerator showing particularly the pedal means for retracting the latch member.

The illustrated embodiment of the invention shown in Figures 1 to 3 comprises a refrigerator case or body 10 having a door 11. Extending inside of the body 10 is a housing or well 12 having an open outer end 13. Pivotaly mounted on a pin 14 is a latching member 15 having a furcated tail portion 16 disposed within the well 12 and a latch head 17 projecting outside of the well. Urging the latch member 15 to latching position is a helical coil spring 18, which is disposed diagonally within the well and has one end disposed within a notch 19 in the well, and the opposite end bearing against the latching member 15 in the region of its pivotal mounting. It will be apparent that the tail portions 16 are adapted to abut against the adjacent side wall of the well for limiting the swinging movement of the latching member in one direction.

Secured by a screw 20 to the free vertical edge of the door 11 is a keeper 21 having a flange 22, against which the head 17 of the latching member is adapted to engage for holding the door in closed position, the keeper engaging surface 23 of the latch head being tapered so that the force of the spring 18 urges the surface 23 against the keeper flange 22 for camming the door into intimate engagement with the body portion.

Formed on opposite sides of the keeper are walls 24, and straddling these walls is a yoke por-

tion 25 of an L-shaped handle 26, rivets 27 extending through the outer portion to the yoke 25 and the adjacent walls 24 of the keeper provide a pivotal mounting for the handle. The handle 26 has a shoulder 28, which abuts against the keeper 21 as shown in Figure 1, and is normally held in this position by a spring 29, one end of which extends into a socket 30 formed in the handle 26 and the opposite end of which abuts against the keeper 21. The spring 29 is mounted on a rivet 31, which is spaced inwardly from the rivets or pins 27, and is secured at its ends in the side walls 24 of the keeper.

Formed on the handle 26 adjacent the latch head 17 is a curve abutment surface 32. The curved abutment surface and the surface on the end portion of the latch head 17 are designed so that upon slight outward movement of the handle 26 away from the door 11, the latching member 15 is rocked in a counter clockwise direction (Figure 1) to move the latch surface 23 away from the keeper flange 22, and thereby release the door. Upon closing the door the flange 22 engages the cam surface 33 of the latch head to swing the same out of the way to allow the door 25 to move inwardly to such position that the surface 22 is engaged by the latch surface 23.

In the form of the invention shown in Figure 4, the latching member 15^a is similarly pivoted in a well 12^a. The latch 15^a is U-shaped in cross-section, and a spring 18^a is wound about the pivotal mounting and has one end bearing against a wall of the well 12^a and the opposite end bearing against the inside of the latch member. The outer end of the latch member 15^a is turned inwardly, as indicated at 34, to engage a curved keeper surface 35. Adjacent the surface 35 is an angular cam surface 36, which engages a latch member when the door is closed to cam it out of the way.

The handle 26^a is pivoted on a pin 37, and an abutment portion 38 on the handle is adapted to engage the outer end of the latching member 15^a and rock it out of engagement with the keeper surface 35. A spring 39 normally holds the handle 26^a against the keeper, which serves as an abutment for limiting the swinging movement of the handle in a direction toward the door. It will be readily understood that this latch operates similar to the one above described. Release of the door may be accomplished by swinging the handle 26^a outwardly to move the latch member 15^a away from the keeper, and upon slamming the door the cam surface 36 cams the latching member 15^a out of the way.

the spring 18^a snapping the latching member into engagement with the keeper surface 35.

To enable the latching member 15^a to be retracted by pedal means so that the door can be released by operation of a person's foot, a yoke 40 surrounds the well 12^a and has an offset portion 41 in which one end of a pin 42 is disposed. The pin 42 slides through a wall of the well 12^a and bears against the inner end of the latching member 15^a. It will be apparent that by downward movement of the yoke 40, the pin 42 is forced inwardly by engagement of a cam surface 43 adjacent the offset portion 41. This operates to rock the latching member 15^a sufficiently to release the keeper, thereby to allow the door to open.

For actuating the yoke 41 a link 44 extends downwardly and is suitably connected to a pedal 45. The pedal 45 is in a convenient position to be depressed by a person's foot, so that a person whose hands are filled with dishes can open the refrigerator door without setting the dishes down. A suitable spring 46 returns the yoke 40 to its original position, and the spring 18^a returns the latching member 15^a to its former position, the pin 42 being returned by the action of the latching member into the offset portion 41 of the yoke.

It is to be understood that numerous changes in details of construction, arrangement and operation may be effected without departing from the spirit of the invention as defined in the appended claims.

What I claim as new and desire to secure by Letters Patent is:

1. A latch mechanism for securing a swinging door to a body comprising a handle pivotally mounted on the door, a keeper on the door having a tapered face and curved latch engaging surface, a stop for said handle, spring means recessed within said keeper to urge the handle toward said stop, a latching member having a

portion recessed within the body and another portion extending outwardly therefrom in position to engage said latching surface, spring means urging said latching member toward and into engagement with said latching surface, and abutment means on the handle engageable with an end portion of said latching member for moving the same away therefrom. 5

2. Latch mechanism for securing a swinging door to a body comprising a pivotally mounted 10 handle provided with a recess adjacent its pivotal mounting, a keeper on the door juxtaposed to said recess, a stop for said handle, a spring recessed within said keeper to urge said handle towards said stop, a latching member having 15 a portion recessed within the body and another portion extending outwardly therefrom to engage said keeper, spring means urging said latching member into engagement with the keeper, and abutment means on said handle engageable 20 with said latching member for moving same from engagement with said keeper.

3. Latch mechanism for securing a swinging door to a body comprising a pivotally mounted handle provided with a recess adjacent its pivotal mounting, a keeper on the door juxtaposed to said recess, a stop for said handle, a spring recessed within said keeper to urge said handle towards said stop, a latching member having a portion recessed within the body and another 30 portion extending outwardly therefrom to engage said keeper, spring means urging said latching member into engagement with the keeper, an inclined surface on one of said keeper and latching members and engageable by the other member 35 to cause said latching member to retract from latching position upon slamming of the door, and abutment means on said handle engageable with said latching member for moving 40 same from engagement with said keeper. 40

DORR MILLER.
